UNITED STATES PATENT OFFICE.

DAVID L. TEMPLE, OF FLORAL PARK, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 5, 1921. Serial No. 458,659.

To all whom it may concern:

Be it known that I, DAVID L. TEMPLE, a citizen of the United States, residing at Floral Park, in the county of Nassau, State 5 of New York, have invented certain new and useful Improvements in Telephone-Exchange Systems, of which the following is a full, clear, concise, and exact description.

This invention relates to a telephone exchange system in which connections are extended by means of machine switching mechanism, and more particularly, to apparatus in manual terminating offices of such 10 an exchange for transmitting busy signals 15 to calling subscribers if desired lines are busy.

In a large telephone exchange during the transition period from a manual to an automatic operating basis, many offices of the 20 exchange are operated upon a manual basis as to calls local to the office and are arranged to terminate calls originating in mechanical offices of the exchange by means of plug ended trunks. The numbers of lines desired 25 by calling subscribers in mechanical offices are displayed before operators in the manual office by means of call indicating devices. Subscribers' lines in such manual offices may 30 also be called from other manual offices of the same exchange in the well-known manner.

When a desired line in such a manual office is tested and found to be busy, it then becomes necessary to apprise the calling subscriber of that fact. In order that no confusion shall arise it is desirable that a busy signal of the same character be employed throughout the exchange regardless of whether the calling subscriber is a subscriber 35 whose line terminates in an office equipped for manual or automatic operation or where the desired line terminates. It is further essential that the character of the busy signal, if universally employed throughout the 40 exchange, shall be such as will flash supervisory lamps at originating manual offices, but will not operate call charging mechanism associated with the switching mechanism of mechanical offices.

Heretofore this result has been accomplished through the provision of two groups of busy back jacks at such manual offices, one group being employed in connection 45 with terminating trunks extending to originating manual offices and the other group

in connection with terminating trunks extending to originating mechanical offices. As the provision of two groups of busy back jacks tends to confusion and the false charging of calls to calling subscribers in mechanical offices through the inadvertent employment of a busy back jack of the wrong group, and since it is further necessary to train the operators in the proper use of the two groups of jacks, it is desirable to provide a single group of jacks which may be used for calls incoming from both manual and mechanical offices. It is therefore an object of this invention to provide a busy back jack and associated circuits which is 60 65 70 arranged for use with terminating trunks extending from either a manual or a mechanical office.

A further object of the invention is the provision of means for rendering the busy 75 back circuit inoperative and for giving an alarm should the circuit become unstandard to such an extent as would cause false call charging if employed to transmit a busy signal to a subscriber in a mechanical office. 80

A still further object of the invention is the provision of means for giving an alarm in case the tip and ring contacts of any busy 85 back jack of a group of jacks become short-circuited.

Further features of the invention will be apparent from the following description taken in connection with the accompanying drawings, in which—Fig. 1 shows apparatus at a mechanical office of an exchange, comprising one of a plurality of subscribers' lines terminating in such mechanical office, a line switch individual to the subscriber's line, a district selector for extending a connection from the subscriber's line to inter-office trunks extending to other offices of the exchange or to other switches of the same office, and an office sender shown diagrammatically within the dotted rectangle for controlling the operation of the district 90 selector and the apparatus in other exchanges of the office to which a connection 95 may be extended. 100

Fig. 2 shows one of a group of interoffice trunks terminating at an operator's position 0 in a manual office, a subscriber's line terminating in such manual office and a busy back jack for associating the busy jack mechanism shown in Fig. 3 with the inter-office trunk, in the event that the desired 105 110

subscriber's line is found to be busy. A relay call indicator is also indicated by the small rectangle in the lower left-hand portion of Fig. 2 for indicating to the operator the designation of the line desired by the calling subscriber.

Fig. 3 shows the circuits of busy back mechanism associated with the busy back jacks shown in Fig. 2 together with alarm 10 circuits for indicating an unstandard condition of the busy back mechanism.

Fig. 4 shows diagrammatically circuits for extending connections to the operator's position 0 of a manual office directly from a 15 mechanical office through a district selector, or indirectly from a mechanical office through a special operator's position 0², and also circuits for extending a connection to the manual office from another manual office of the same exchange, also the line of a manual subscriber terminating in the manual office and busy back jacks for cooperation with the terminating circuits of the manual office for transmitting a busy 20 signal to a calling subscriber in either a mechanical or manual originating office.

The line switch 106 is of the well-known step-by-step type controlled in its step-by-step movement by the stepping magnet 102. 30 The district selector 150 is of the so-called panel type shown in the patent to E. B. Craft and J. N. Reynolds 1,123,696, issued January 5, 1915, but has been disclosed herein in an abbreviated form for the purpose of simplifying the disclosure of this 35 invention. The switch has been illustrated as having but a single set 147 of brushes, the switch being set to a desired group of terminals by a single selective movement 40 under the control of the updrive magnet 143.

The sequence switch 198 associated with the district selector is of the well-known type disclosed in the patent to J. N. Reynolds and C. F. Baldwin, No. 1,127,808, issued February 9, 1915. The office sender disclosed in the dotted rectangle is of the type disclosed in the patent to F. A. Stearn and F. J. Scudder, No. 1,395,977, issued 50 November 1, 1921, only so much of this sender being disclosed herein as is considered necessary to an understanding of this invention.

The relay call indicator, shown in the small rectangle on Fig. 2, may be of the type disclosed in the application of A. E. Lundell and E. H. Clark, Serial No. 387,531, filed June 9, 1920, but since a complete disclosure of the circuits of this indicator is not essential to an understanding of this invention they have not been disclosed herein.

Having now briefly described the invention and the apparatus employed, it is 65 thought that a clearer understanding of the

invention may be had from a more detailed description of the manner in which connections are established. It will first be assumed that the calling subscriber A in a mechanical office of the exchange desires a 70 connection with the subscriber's line B which terminates in a manual office of the exchange and that the line of the desired subscriber is at the time free. The calling subscriber to initiate the call removes his 75 receiver from the switchhook, whereupon a circuit is established for the line relay 100 extending through the armature contacts of the cut-off relay 101, over the calling line loop. Line relay 100, upon energizing, establishes a circuit for the stepping magnet 102 which in the well-known manner advances the wipers 103, 104 and 105 of the line switch 106 over the terminals of trunk lines extending to district selector switches. 80 As soon as an idle district selector is found, a circuit is established for the cut-off relay 101 of the calling line which may be traced from battery through the operating winding of relay 110, cam contact 111, bank 85 terminal 109 and test wiper 105 of line switch 106 and to ground through the winding of cut-off relay 101 and the winding of a message register magnet 112. Relays 110 and 101 energize in this circuit, but 90 magnet 112 being marginally wound does not receive sufficient current at this time to energize. Upon the energization of cut-off relay 101, the circuit of the subscriber's line relay 100 is opened and the advance 100 of the line switch is thereupon arrested.

Relay 110, upon energizing, closes a circuit for advancing sequence switch 198 of the selected district selector 150 out of position 1 and into position 2, which circuit extends from battery through the magnet winding of sequence switch 198, cam contact 113 (1) and to ground at the right-hand armature contact of relay 110. With sequence switch 198 in position 2, a circuit is 105 established for the stepping magnet 116 of the sender finder switch SF for advancing the sender finder in search of an idle office sender. The circuit of stepping magnet 116 may be traced from battery through the winding and armature contact of magnet 116, cam contact 117 (2) and thence to ground at the left-hand armature and contact of relay 118. During the hunting movement of sender finder SF, the test wiper 119 advances over test terminals of office senders until the wiper 119 engages the test terminal of an idle sender, when a circuit is established for relay 118 extending from battery through the winding of this relay, 119 wiper 119 and terminal 120 to ground. Relay 118, upon energizing, opens the previously traced circuit of stepping magnet 116 thereby arresting the movement of the sender finder and closes a circuit for advanc- 125 130

ing sequence switch 198 into position 3, which circuit extends from battery through the magnet winding of the sequence switch, through cam contact 121 (2) and to ground 5 at the armature contact of relay 118.

Upon the association of an idle office 10 sender with the selected district selector, an impulsing circuit is established between the office sender and the calling line over which circuit the calling subscriber is enabled 15 through the operation of his calling dial S to register the number of the desired line upon the registers of the sender. This impulsing circuit may be traced from battery 20 through the register stepping relay 123, wiper 124, conductor 125, the left-hand contact of cam 126 (1 to 3), bank terminal 108 and wiper 104 of line switch 106, thence over the calling subscriber's line loop and 25 through his calling dial S, wiper 103 and bank terminal 107 of line switch 106, the lower contact of cam 127 (1 to 3), conductor 128, wiper 129 and thence to ground.

With sequence switch 198 in position 3, 30 a fundamental circuit is established between the district selector 150 and the selected office sender, which may be traced from battery through the winding of control relay 131, cam contact 132 (3), conductor 134, wiper 135, the winding of sender stepping relay 136, the contact of cam 130 which cam is associated with a sequence switch (not shown) associated with the office sender, the armature and back contact of counting relay 137, wiper 35 138, conductor 139 and thence to ground at cam contact 140 (3 to 4). Relays 136 and 131 energize in this circuit, relay 131 closing a locking circuit for itself through its left-hand armature, cam contact 133 (3 to 4) 40 and thence to conductor 134 and over the fundamental circuit previously traced, and at its right-hand armature closing a circuit extending through cam contact 142 (3) and conductor 141 for advancing sequence switch 45 198 into position 4.

With sequence switch 198 in position 4 a circuit is now established for the updrive magnet 143 for advancing the brush set 147 of the district selector 150 in search of a 50 group of trunk lines extending to the office of the exchange in which the desired line B terminates. The circuit of magnet 143 may be traced from battery through the winding of magnet 143, cam contact 144 (4) and to ground at the right-hand armature of relay 131. Magnet 143, upon energizing, presses the depending portion of switch shaft 145 against the constantly rotating updrive roller 146, whereupon the switch shaft and the attached brush set 147 is driven upwardly.

As the brush set 147 approaches a position 55 immediately beneath the first group of bank terminals, shaft wiper 148 engages a conducting portion of commutator 149, where-

upon a circuit is closed in shunt of the winding of the sender stepping relay 136 which may be traced from battery through the winding and left-hand armature and contact of control relay 131, the cam contact 133 70 (3 to 4), cam contact 151 (4), conductor 152, commutator 149 and thence to ground through wiper 148. In response to the establishment of this shunt circuit, sender stepping relay 136 deenergizes and in the 75 well-known manner controls the circuits of the sender to count one impulse on the counting relays of the office sender.

As the switch shaft 145 continues in its upward movement, the shaft wiper 148 engages an insulating portion of commutator 149 and the previously traced shunt circuit is thereupon opened, again permitting the energization of sender stepping relay 136. Thus, during the continued upward movement of the switch shaft, the sender stepping relay 136 is intermittently energized and deenergized, until the 0' counting relay 80 137 becomes energized when the office sender will be satisfied with respect to the 90 office registration of the desired subscriber's line. Upon the energization of relay 137, the previously traced fundamental circuit is opened, thereby opening the circuit of control relay 131. As soon following the opening of the fundamental circuit as the brushes of brush set 147 are centered upon the lowermost set of bank terminals in the selected group, shaft wiper 148 will engage 95 an insulating portion of commutator 149 and relay 131 will become deenergized, opening the circuit of updrive magnet 143 to arrest the upward movement of the switch shaft and closing a circuit extending through cam contact 153 (4), and over conductor 141 for advancing sequence switch 100 198 into position 5.

With sequence switch 198 in position 5 the circuits of the district selector are prepared for controlling the district selector in 110 its hunting movement for selecting an idle trunk in the selected group of interoffice trunks. A circuit is now established for relay 131 extending from battery through the winding of the relay, cam contact 132 115 (5) and to ground at cam contact 154 (5) and at its right-hand armature contact closes a circuit extending over cam contact 142 (5), and conductor 141 for advancing sequence switch 198 into position 6.

Under the assumption that the first trunk 120 of the selected group, upon the bank terminals of which the brush set 147 is now resting, is at the time busy, relay 131 is maintained locked after sequence switch 198 leaves position 5 over a circuit extending through the left-hand armature of relay 131, cam contact 133 (5 to 6), cam contact 155 (5½ to 10), test brush 156, test terminal 125 157, thence over multiples of test terminal 130

157 to ground through the test brush 156 of a district selector similar to selector 150 which is at the time in engagement with the multiples of this trunk, and to ground at a 5 cam contact corresponding to cam contact 163.

With sequence switch 198 in position 6, the circuit of updrive magnet 143 is again established over cam contact 144 (6) and the 10 switch shaft 145 is again driven upwardly in search of an idle trunk in the selected group. So long as the test brush 156 engages the test terminals of busy trunks, the locking circuit of control relay 131 is maintained and the circuit of the updrive magnet 143 remains closed. As soon, however, 15 as test brush 156 engages the test terminal of an idle trunk, which it will be assumed is the trunk terminating in bank terminals 158, 166 and 167, the previously traced locking circuit of control relay 131 is opened and, as soon as the brushes of brush set 147 become centered upon the bank terminals of the idle trunk, relay 131 deenergizes. Until the brushes are so centered, relay 131 is 20 maintained locked over its left-hand armature, cam contact 133 (5 to 6), cam contact 161 (6), conductor 162, centering commutator segment 160 and to ground on shaft 25 wiper 159. Upon the deenergization of control relay 131 the circuit of the updrive magnet 143 is opened to arrest the upward movement of the switch shaft and a circuit is established over cam contact 153 (7 to 8) 30 and conductor 141 for advancing sequence switch 198 into position 8, in which position conductors 134 and 139 of the fundamental circuit extending to the office sender are connected over cam contacts 174 and 175 to 35 the brushes 165 and 164 of the district selector 150.

During the setting of the district selector switch 150, relay 168 is maintained energized over a circuit extending from battery 40 through the winding of relay 168, the left-hand contacts of cam 169, wiper 170, the armature and back contact of advance relay 171 of the office sender and to ground at cam contact 172, and at its right-hand armature and contact closes a circuit for energizing control relay 131 which is effective 45 as soon as sequence switch 198 reaches position 8. This circuit extends from battery through the winding of relay 131, cam contact 173 (8) and to ground at the right-hand armature of relay 168. Relay 131 is maintained energized until the office sender has 50 functioned to complete its control over apparatus associated with the incoming end 55 of the selected interoffice trunk at the distant manual office.

With sequence switch 198 in position 8, 60 busy potential is connected from ground at cam contact 163 (7 to 17), over brush 156 65 to test terminal 158 for marking the se-

lected interoffice trunk "busy" to other district selectors having access thereto.

A circuit is now extended from the office sender for energizing the line relay 200 at the incoming end of the selected interoffice trunk, which circuit may be traced from battery through the right-hand winding of relay 200, conductors 201 and 202, the upper left-hand winding of repeating coil 203, trunk conductors 204 and 205, bank terminal 167 and brush 165 of district selector 150, cam contact 174 (7 to 8), conductor 134, wiper 135, winding of sender stepping relay 136, cam 130, the armature and back contact of counting relay 137, wiper 138, conductor 139, cam contact 175 (7 to 8), brush 164 and bank terminal 166 of district selector 150, trunk conductors 206 and 207, the lower left-hand winding of repeating coil 203, conductors 208 and 209 and to ground through the left-hand winding of relay 200. Relay 200, upon energizing, closes a circuit for relay 212 which may be traced from battery, conductors 214 and 213, winding of relay 212, conductors 211 and 210 to ground at the 90 armature contact of relay 200. Relay 212, upon energizing, locks to battery on conductor 215 and closes a circuit over conductor 232 for the assignment lamp 216.

The operator at position 0 noting the illumination of assignment lamp 216 individual to the selected trunk, depresses the assignment key K individual to such trunk, whereupon a circuit is established for assignment relay 218 which may be traced from battery over conductor 219, the right-hand winding of relay 218, conductor 217 and thence to ground through the contact of key K. Relay 218, upon energizing, locks to battery on conductor 219 through both of its 100 windings independently of the contacts of key K and closes an obvious circuit for relay 221. Relay 221, upon energizing, opens the initial energizing circuit of relay 212 and closes a circuit for relay 223 which may be 110 traced from battery over conductors 215 and 213, conductor 222 and thence to ground through the winding of relay 223.

With relays 218 and 223 energized a circuit is now established for relay 224 for associating a relay call indicator, common to the trunks of the operator's position, with the selected trunk 205, 206. The circuit of relay 224 may be traced from battery 115 through the left-hand armature and contact of relay 223, conductor 225, the winding of relay 224, conductor 226, conductor 259 and thence to ground at the armature contact of relay 227. The fundamental circuit previously traced from the office sender to the brushes 165 and 164 of the district selector switch is now extended over bank terminals 167 and 166, trunk conductors 205 and 206, armature contacts of relay 224 and conductors 230 and 231 to the relay call indicator 125 130

cator mechanism represented in the small rectangle labelled "Relay call indicator" and the office sender functions in the well-known manner to transfer the line number registered upon its numerical registers to the relay call indicator mechanism for indicating to the operator at position 0 the number of the line desired.

Upon the energization of relay 224 and the 10 association of the relay call indicator mechanism with the conductors 205 and 206 of the trunk circuit, the circuit previously traced for relay 200 is opened at the armature contacts of relay 224 and relay 200 deenergizes, 15 opening the locking circuit of relay 212. The previously traced circuit of lamp 216 is now opened and since at this time relay 221 is energized, a new circuit for lamp 216 is established, extending from battery through 20 the lamp, over conductor 233, conductor 234 and to ground through interrupter 235 for causing the lamp 216 to flash. This lamp continues to flash during the setting of the 25 relay call indicator and until the operator inserts the plug P in which the selected trunk circuit terminates, in the jack of the line indicated by the illuminated lamps of the indicator. Upon the deenergization of relay 212, the initial energizing circuit of 30 relay 223 is opened, but relay 223 now remains locked over conductor 229 and to battery through the winding of relay 228, thereby causing the energization of relay 228.

Following the completion of the setting 35 of the relay call indicator, relay 260 associated with the indicator energizes in the manner fully set forth in the aforesaid application of A. E. Lundell and E. H. Clark, and opens the circuit of relay 224. The relay call indicator is now disconnected from the conductors 205 and 206 of the trunk 40 circuit and the circuit of relay 200 is again established. Relay 200 upon reenergizing closes a locking circuit for relay 228 over conductor 210 and establishes a direct shunt 45 to ground around the winding of relay 223. Relay 223 thereupon deenergizes.

The operator noting the flashing of lamp 216 and the illumination of lamps of the 50 call indicator, takes up the plug P of the trunk circuit corresponding to the flashing lamp 216 and in the well-known manner tests the sleeve of the jack of the line indicated by the indicator to determine if the 55 desired line is idle and free to receive the desired connection. Under the assumption that the desired line B is idle, the operator inserts the plug P in the jack J of the line, whereupon a circuit is established which 60 may be traced from battery through the winding of relay 241, conductor 240, conductor 239, conductor 238, the winding of relay 220, conductor 237, sleeve contacts of plug P and jack J and thence to ground 65 through the winding of cut-off relay 236 of

the line B. Relays 236, 220 and 241 energize in this circuit, relay 220 establishing the continuity of the tip strand of the trunk circuit and opening the locking circuit of relay 218. Relay 218, upon deenergizing, 70 now opens the circuit of relay 221, which in turn, opens the circuit previously traced extending through lamp 216 and interrupter 235. Disconnect lamp 242 is not illuminated at this time as it is shunted by the 75 winding of relay 241.

Since at this time the office sender has completed its functions, advance relay 171 becomes energized in the manner set forth in the patent to F. A. Stearn and F. J. Scudder hereinbefore referred to, removing the shunt around resistance element 176. The current now flowing through the winding of relay 168 is reduced to such an extent that this relay deenergizes, opening the circuit of relay 131, which upon deenergizing, 80 closes a circuit extending over cam contact 153 (7 to 8) and conductor 141 for advancing sequence switch 198 into position 10. The office sender is now restored in the 85 well-known manner and disassociated from the district selector switch 150, whereupon it is rendered available for use in establishing other connections.

With sequence switch 198 in position 10, 90 relay 200 of the selected interoffice trunk is energized over a circuit which may be traced from battery through its right-hand winding, conductors 201 and 202, the upper left-hand winding of repeating coil 203, conductors 204 and 205, bank terminal 167 and brush 165 of the district selector 150, cam contact 177 (10), the upper right-hand winding of repeating coil 178, the winding of polarized relay 179, the lower right-hand 100 winding of repeating coil 178, cam contact 180 (10), brush 164 and bank terminal 166 of district selector switch 150, trunk conductors 206 and 207, the lower left-hand winding of repeating coil 203, conductors 105 208 and 209 and thence to ground through the left-hand winding of relay 200. Current flowing in this circuit while in such a direction as to energize relay 200, does not 110 flow through the windings of polarized relay 179 in such a direction as to cause its effective energization.

The operator to call the subscriber B now depresses the ringing key 242 for connecting the source of ringing current 250 to the 115 called line. In response to the application of ringing current, the called subscriber removes his receiver from its switchhook thereby establishing a circuit for the supervisory relay 243 which may be traced from 120 battery through the lower right-hand winding of repeating coil 203, the winding of relay 243, conductor 244, the lower normal contact of ringing key 242, the ring contacts of plug P and jack J, thence over the 125 130

subscriber's line loop, through tip contacts of jack J and plug P, the upper normal contacts of ringing key 242, conductor 245, conductor 246 and thence to ground through the upper right-hand winding of repeating coil 203. Relay 243, upon energizing with relay 241 energized, establishes a circuit for reversing relay 247 which extends from battery through the winding of relay 247, conductor 248, conductor 249 and thence to ground at the armature contact of relay 241. Relay 247, upon energizing, reverses the connection of the windings of relay 200 to conductors 205 and 206, respectively, whereupon current flows through the windings of polarized relay 179 in such a direction as to cause its effective energization. A circuit is now established at the district selector for relay 181 which may be traced from battery over contact 182 of the circuit interrupting cam 183, the winding of relay 181, cam contacts 183 and 184 of sequence switch 198, closed in position 10 and thence to ground at the contact of polarized relay 179. Relay 181, upon energizing, closes a locking circuit for itself independently of cam contact 182 and prepares a circuit for charging relay 168 which is effective as soon as cam 183 moves to such a position as to cause the closure of its contact 185. Relay 168, upon energizing, closes a locking circuit for itself extending over the upper contacts of cam 169 and to ground through its own right-hand armature contact, and at its left-hand armature contact prepares a circuit over conductors 190 and 191 which is effective for charging a call on the calling subscriber's message register 112 following the termination of the conversation and the movement of the sequence switch 198 into position 17.

The calling subscriber A is now connected in a conversational circuit with the subscriber B over the conductors shown in heavy lines in Figs. 1 and 2, the calling subscriber receiving talking current through the left-hand winding of repeating coil 178 and the called subscriber receiving talking current through the right-hand winding of repeating coil 203. During the continued establishment of the talking circuit, the supervisory relays 186 and 243 are maintained energized. Upon the termination of the conversation, the subscribers restore their receivers to their respective switchhooks, whereupon relays 186 and 243 become deenergized. Relay 186, upon deenergizing, closes a circuit extending over conductor 187 and cam contact 188 (5 to 16) for advancing sequence switch 198 out of position 10 and into position 16. As soon as sequence switch 198 leaves position 16, the previously traced circuit for relay 110 is opened at cam contact 111, but relay 110 is maintained energized over a circuit extending from battery through its right-hand operating winding, conductor 191, the left-hand armature contact of relay 168, conductor 190, cam contact 189 (17), bank terminal 109 and wiper 105 of line switch 106 and thence to ground through the windings of cut-off relay 101 and message register magnet 112. Booster battery current is also connected through the winding of message register magnet 112 from booster battery, through cam contact 193 (17), cam contact 192 (17), the left-hand armature contact and left-hand non-inductive winding of relay 110, conductor 191, the left-hand armature contact of relay 168, conductor 190 and thence to ground through the winding of magnet 112 over the circuit previously traced. Magnet 112 now receives sufficient current to cause its energization, thereby causing the registration of a call on the calling subscriber's message register.

With sequence switch 198 in position 17 a circuit is now established for relay 131 which may be traced from battery through the winding of relay 131, cam contact 132 (17), and thence to ground through cam contact 154 (17). Relay 131, upon energizing, closes a circuit over cam contact 142 (17), and conductor 141 for advancing sequence switch 198 out of position 17 and into position 18. As soon as sequence switch 198 leaves position 17, the circuit previously traced through the windings of cut-off relay 101 and the message register magnet 112 is opened at cam contact 189 and the circuits associated with the calling subscriber's line and individual line switch are thereby restored to normal condition in the well-known manner. With sequence switch 198 in position 18 a circuit is now established for the downdrive magnet 194 extending through cam contact 195 (18) for energizing the downdrive magnet 194. This magnet upon energizing presses the depending portion of switch shaft 145 against the downdrive roller 199, thereby causing the downward movement of the switch shaft into normal position. As soon as the switch shaft reaches its normal position, shaft wiper 148 engages the normal commutator segment 196 and a circuit is established from ground on shaft wiper 148, through segment 196, cam contact 197 (18), and over conductor 141 for advancing sequence switch 198 into normal position. The circuits of the district selector are now in normal position.

As soon as sequence switch 198 leaves position 17, busy potential is removed from test terminal 158 of the selected interoffice trunk and this trunk is made available for other calls. Upon the movement of the district selector switch 198 out of position 10, the circuit previously traced through the winding of trunk relay 200 is opened at cam contacts 177 and 180 and relay 200 deenergizes, opening the locking circuit of relay 228. Re-

lay 228, upon deenergizing, disconnects relay 241 from the circuit previously traced over the sleeve conductor 237 of the trunk in shunt of the disconnect lamp 242 and the lamp 242 now becomes illuminated over a circuit extending from battery through the lamp, the winding of relay 220, conductor 237, sleeve contacts of plug P and jack J to ground through the winding of relay 236.

10 The operator in position 0 noting the illumination of lamp 242 removes the plug P from the jack J, whereupon the lamp 242 becomes extinguished and relays 220 and 236 become deenergized. All of the apparatus at the 15 manual office employed in the establishment of the connection is now restored to normal position.

If at the time the operator at position 0 tests the jack of the desired line she finds the 20 line busy, she inserts the plug P of the trunk circuit in a busy-back jack J' of a group of jacks at her position for the purpose of transmitting a busy back signal to the calling subscriber's line. Upon the insertion 25 of the plug P in the jack J', a circuit is established from battery through the winding of relay 241, conductor 240, conductor 239, conductor 238, the winding of relay 220, sleeve conductor 237, the sleeve contacts 30 of plug P and jack J', conductor 249 and to ground through the winding of relay 300. Relay 300, upon energizing in this circuit, establishes a circuit for the busy-back relay 302 extending from battery at the armature contact of relay 305, over conductors 304 and 303, through the winding of relay 302 and to ground through the busy-back interrupter 301. Busy-back relay 302 is intermittently operated in this circuit and at 40 its left-hand armature and alternate contact establishes a connection from ground through the secondary winding of tone coil 306 to the ring contacts of all busy-back jacks of the group.

45 The circuit closed over the ring contact of the jack J' upon the operation of relay 302 may be traced from ground through the secondary winding of tone coil 306, the outer left-hand armature and contact of relay 302, 50 ring conductor 307, ring contact of jack J', ring contact of plug P, the lower normal contact of ringing key 242, conductor 244, the winding of relay 243, the lower right-hand winding of repeating coil 203 and 55 thence to battery and ground. The intermittent closure of this circuit through the operation of relay 302 causes the intermittent operation of relay 243 and the intermittent reversal of current through the 60 winding of polarized relay 179 at the district selector 150. Tone current which is also transmitted from the primary of the tone coil 306 inductively into the circuit traced through the lower right-hand winding of repeating coil 203 is inductively

transmitted over the interoffice trunk through the right-hand winding of repeating coil 178 and thence inductively to the calling subscriber's line to apprise the calling subscriber of the fact that the desired line is busy.

The circuit closing periods of the busy-back interrupter 301 are so designed that the intermittent periods during which polarized relay 179 closes the circuit of relay 181 at the district selector are of such short duration that the circuit closing can 183 does not have time to close the circuit of charging relay 168 before relay 181 becomes unlocked and deenergized and thus the call 80 charging circuits of the subscriber's district selector are not conditioned for charging a call on the subscriber's message register.

At the busy-back circuit, relay 308 is intermittently operated through the rotation 85 of busy back interrupter 301, but is functionless unless a permanent ground exists on the circuit through the busy-back relay 302 through the failure of the busy back interrupter to operate properly or from any 90 other cause. In such an event, relay 308 is energized for a sufficient time to establish a circuit for relay 313 which may be traced from the permanent ground through the armature contact of relay 308, conductor 95 314, the winding of relay 313, conductor 312, conductor 311 and thence to battery through the armature contact of relay 310, which latter relay operates during a ringing interval of the ringing current interrupter 309. The energizing circuit of relay 310 may be traced from ground through the winding of the relay, condenser 331, the ringing interrupter 309 and thence to 100 ground through the ringing generator 319. Upon the energization of relay 313 a circuit 105 is established for relay 315 which may be traced from battery through the winding of relay 315, the right-hand armature and contact of relay 313, the winding of relay 313, conductor 110 314, the armature and contact of relay 308 and thence to the permanent ground. Relay 315 now prepares a circuit for relay 305 which may be traced from ground through the left-hand armature and contact of relay 313, the winding of relay 305, conductor 316, the armature and alternate contact of relay 315, conductor 311 and to the front contact of relay 310 which circuit is closed upon the next ringing period 115 120 of the ringing interrupter 309.

Relay 305, upon energizing, closes a locking circuit for itself extending from battery through its right-hand armature contact and winding to ground at the left-hand armature and contact of relay 313 and at its left-hand armature and normal contact opens the circuit extending through the busy-back relay 302 to prevent the operation of relay 302 in the event that an 125 130

- operator plugs into a busy-back jack of the group during the time that the busy back circuit is unstandard by reason of the permanent ground. By thus rendering the busy back circuit inoperative, a steady ground connection over the sleeve contact of the busy-back jack is prevented and thus the false operation of a calling subscriber's message register is obviated.
- 10 Instead of employing the ringing current interrupter 309 for timing the operation of the chain of relays 305, 313 and 315, any other suitable timing device as a chain of slow acting delays might be employed.
- 15 Relay 305 upon energizing also closes a circuit from battery extending over conductor 318 to ground through the winding of alarm relay 317 for the purpose of operating an alarm signal 322 at the chief operator's position, an alarm 321 at the wire chief's desk and for ringing a bell alarm 320 at the wire chief's desk. The circuit for alarm bell 320 may be traced from ground through the bell magnet windings, the left-hand armature and contact of relay 317, the ringing current interrupter 309 and from ground to the source of ringing current 319. This inoperative condition of the busy back circuit is maintained through the operation of relay 305 until the proper steps have been taken to clear the trouble, when the circuit is again placed in operative condition.
- 30 Should a cross connection appear between the tip and ring contacts of any busy back jack of the group, then when an operator plugs into such jack thereby causing the energization of busy-back relay 302, a circuit is established for relay 324 which may be traced from ground through the winding of relay 324, the right-hand armature and contact of relay 302, the tip and ring contacts of the defective jack, the ring contact of plug P, the lower normal contact of ringing key 242, conductor 244, relay 243 and thence to battery and ground through the lower right-hand winding of repeating coil 203. Relay 324, upon energizing, establishes a circuit for relay 325 which may be traced from ground through the armature and contact of relay 324, the winding of relay 325, condenser 332, ringing interrupter 309, and thence to ground through the ringing current generator 319. Relay 325 is intermittently operated in this circuit and at its armature and contact establishes an intermittent energizing circuit for relay 317, which in turn, causes the lamps 321 and 322 to be flashed. In response to these flashing signals, operators at either the chief operator's position or wire chief's desk take the proper steps to have the trouble at the defective jack cleared. It is obvious that a permanent cross between the tip and ring contacts of the busy-back jack would cause a

steady operation of relay 243 at the operator's terminating trunk, which in turn, would cause the registration of a call on the calling subscriber's message register.

Should a false ground exist on the ring conductor 307 of any jack of the group due to any cause such as a cross connection between the sleeve and ring or ring and tip contacts of such jack, then when the operator plugs into one of the jacks this ground potential 70 while effective to cause the energization of relay 243 irrespective of ground applied through the energization of relay 302, is ineffective to cause the continued operation of the supervisory relay 243 of the trunk circuit and the false charging of a call since at this time and upon each deenergization of busy-back relay 302 the ring conductors 307 of the jacks are connected to battery through the winding of low resistance relay 353. 80 The winding of relay 353 being of low resistance and being in shunt of the winding of relay 243 shunts the current away from relay 243 and prevents the continued energization thereof during the intervals that 85 busy-back relay 302 is deenergized. Relay 353 energizes however and closes a circuit over conductor 354 for causing the intermittent operation of relays 325 and 317 and the flashing of signals 321 and 322. The flashing of signals 321 and 322 indicates that there is trouble on one of the busy-back jacks.

If a connection is extended to a trunk circuit at the operator's position 0 100 through a semi-mechanical operator's position, such as shown at 0² in Fig. 4, the operation of the busy-back relay 302 under the control of busy-back interrupter 301 causes the intermittent operation of the polarized relay 375 at the semi-mechanical position, which in the well-known manner, causes the flashing of a supervisory signal at the operator's position 0². Likewise, if a call has been extended to the manual office from an 110 originating manual office over a plug ended trunk circuit terminating in the terminating office at the operator's position 0', the connection of such trunk circuit at such position 0' with the busy back circuit causes the intermittent operation of the busy back relay 302, which in turn, causes the flashing of a supervisory signal in the originating office in the well-known manner. In the diagram in Fig. 4, the manner in which these three 115 types of connections may be established to a terminating manual office have been schematically disclosed. A calling subscriber, for example, may obtain connection directly with the terminating manual office over a 120 line switch 106, district selector 150 and trunk circuit 205, 206 as illustrated in detail in Figs. 1 and 2, or through the district selector 150, the trunk circuit 350 and 351, the semi-mechanical cord circuit at the special 125 130

A operator's position 0² and the district selector 352 in which the semi-mechanical cord circuit terminates.

What is claimed is:

5. 1. In a telephone exchange system, calling subscribers' lines, called subscribers' lines, means comprising automatic switching mechanism and plug ended trunk circuits for establishing connections between said 10 lines, call charging means associated with said calling lines, and mechanism common to said trunk circuits and associative therewith over the plugs thereof for transmitting a busy signal to a calling line if the called line 15 is busy, said mechanism being ineffective to cause the operation of the call charging means of said calling line.
2. In a telephone exchange system, a calling subscriber's line, a call charging device 20 associated with said line, an operator's position, a trunk line extending to said position, a second operator's position, a supervisory signal at said latter position, a called subscriber's line terminating in said first operator's position, means for extending a connection from either said subscriber's line or 25 said second operator's position to said called subscriber's line, a busy back jack at said first operator's position and busy-back 30 mechanism associated with said jack for transmitting a busy signal to said calling subscriber's line or to said second operator's position if said called line is busy, said mechanism being effective to operate said 35 signal if the connection is extended from said second operator's position, but ineffective to operate said call charging device if said connection is extended from said calling subscriber's line.
40. 3. In a telephone exchange system, a calling subscriber's line, a call charging device associated with said line comprising a timed operating mechanism, an operator's position, a trunk line terminating in said position, 45 a second operator's position, a called subscriber's line terminating in said first operator's position, means for extending a connection from either said subscriber's line or from said second operator's position to said 50 called subscriber's line, a supervisory signal at said latter operator's position, a busy-jack at said first operator's position, and busy back mechanism associated with said jack for transmitting a busy signal back 55 over the established connection if said called line is busy and for intermittently completing an operating circuit for either said timed operating mechanism or said supervisory signal for periods sufficient to operate said signal but insufficient to operate said call charging device.
4. In a telephone exchange system, a calling subscriber's line, a called subscriber's line, means comprising a plug ended trunk 60 circuit for establishing a connection between
- said lines, call charging means associated with said calling line, a group of busy back jacks, a source of tone current, a relay associated with said jacks, means for intermittently operating said relay when said 70 trunk circuit is associated with one of said jacks for intermittently associating said source of tone current with said jacks and with said calling line, said intermittent application of said source of tone current being ineffective to operate said call charging means.
5. In a telephone exchange system, a calling subscriber's line, a call charging device 80 associated with said line, an operator's position, means for extending a connection from said line to said operator's position, a called subscriber's line terminating in said operator's position, a busy back mechanism for association with said established connection if said called line is busy for transmitting a busy signal to said calling line and means for rendering said mechanism inoperative to transmit said signal if said mechanism is in such an unstandard condition as would erroneously operate said call charging device.
6. In a telephone exchange system, a calling subscriber's line, a called subscriber's line, means comprising a plug ended trunk 90 circuit for establishing a connection between said lines, a call charging device associated with said calling line, means responsive to the answer of said called subscriber for preparing said call charging device for operation, a group of busy back jacks, a source of tone current, an interrupter, a relay associated with said jacks, means for causing said relay to be intermittently operated by 100 said interrupter when said trunk circuit is associated with one of said jacks for associating said source of tone current with said jacks and said calling line for periods of insufficient duration to operate said call charging device and means for rendering said relay inoperative to transmit said signal if a condition prevails at said interrupter such as would maintain said busy tone current associated with said calling line for a period sufficient to operate said 105 call charging device.
7. In a telephone exchange system, a calling subscriber's line, a called subscriber's line, means comprising a plug ended trunk 110 circuit for establishing a connection between said lines, a call charging device associated with said calling line, means responsive to the answer of said called subscriber for preparing said call charging device for operation, a busy back mechanism for association with said trunk circuit for transmitting a 120 busy signal to said calling line if said called line is busy, but ineffective to operate said call charging device, means for rendering said mechanism inoperative to transmit said 125

signal if said mechanism is in an unstandard condition and means for giving an alarm signal until said unstandard condition is removed.

8. In a telephone exchange system, a calling subscriber's line, a call charging device associated with said line comprising a timed operating mechanism, a called subscriber's line, means comprising a plug ended trunk circuit for extending a connection between said lines, means responsive to the answer of said called subscriber for operating said call charging device, a busy back mechanism for association with said trunk circuit for transmitting a busy signal to said calling line if said called line is busy, but for periods less than the operating time of said timed operating mechanism and timing means effective upon an unstandard condition of said busy back mechanism to disconnect said busy back mechanism after a period less than the operating time of said call charging operating mechanism.
9. In a telephone exchange system, a calling subscriber's line, a called subscriber's line, means comprising a plug ended trunk circuit for establishing a connection between said lines, a call charging device associated with said calling line, means responsive to the answer of said called subscriber for preparing said call charging device for operation, a busy-back jack, a source of busy tone current, a relay, means for causing said relay to be intermittently operated when said trunk circuit is associated with said jack for intermittently associating said source of current with said jack and said calling line an alarm device and means effective upon the operation of said relay if the tip and ring contacts of said jack are cross connected to operate said alarm device.
10. In a telephone exchange system, a calling subscriber's line, a called subscriber's line, means comprising a plug ended trunk circuit for establishing a connection between said lines, a call charging device associated with said calling line, a relay associated with said trunk circuit responsive to the answer of said called subscriber for preparing said call charging device for operation, a group of busy back jacks, a source of busy tone current, a relay associated with said group of jacks, means for causing said relay to be intermittently operated when said trunk circuit is associated with one of said jacks

for intermittently associating said source of current with said jacks and with said calling line, and a low resistance relay adapted to be connected in shunt with said first relay and to be operated by a false ground on the ring contact of any one of said jacks for preventing the operation of said call charging device.

11. In a telephone exchange system, a calling subscriber's line, a called subscriber's line, means comprising a plug ended trunk circuit for establishing a connection between said lines, a call charging device associated with said calling line, a relay associated with said trunk circuit responsive to the answer of said called subscriber for preparing said call charging device for operation, a group of busy back jacks, a source of busy tone current, a relay associated with said group of jacks, means for causing said relay to be intermittently operated when said trunk circuit is associated with one of said jacks for intermittently associating said source of current with said jacks and with said calling line, a low resistance relay adapted to be connected in shunt with said first relay and to be operated by a false ground on the ring contact of any one of said jacks for preventing the operation of said call charging device, and a signalling device under the control of said last named relay for indicating an unstandard condition of one of said jacks.

12. In a telephone exchange system, a calling subscriber's line, a call charging device associated therewith comprising a timed operating mechanism, a called subscriber's line, means comprising a plug ended trunk circuit for extending a connection between said lines, means responsive to the answer of said called subscriber for operating said call charging device, a busy-back mechanism for association with said trunk circuit for transmitting a busy signal to said calling line if said called line is busy but for periods less than the operating time of said timed operating mechanism, and a chain of relays operative to disassociate said busy-back mechanism after a period less than the operating time of said call charging operating mechanism if said busy-back mechanism becomes permanently grounded.

In witness whereof, I hereunto subscribe my name this 1st day of April, A. D., 1921.

DAVID L. TEMPLE.
